STRAIGHT BAR KNITTING MACHINE

Filed Aug. 22, 1932

Inventor:
Carl Baumgärtel

UNITED STATES PATENT OFFICE

CARL BAUMGÄRTEL, OF ZEULENRODA, GERMANY

STRAIGHT BAR KNITTING MACHINE

Application filed August 22, 1932, Serial No. 629,957, and in Germany January 29, 1931.

This invention relates to straight bar knitting machines having means for moving the needles into or out of the operative position.

- 5 In machines of this kind, for example when narrowing or widening the fabric, the needles which may be dispensed with or those which are additionally required are moved out of or into the path of the cams.
- 10 For this purpose it has already been proposed to provide operating jacks for the needles, which jacks may be passed into or out of engagement with the cams. These jacks, however, are either in insufficient positive connection with the needles, or special pawls are provided thereon, with which the cams are permitted to engage. In view of the fine divisioning of the needle bed, however, these pawls can only be mounted on the
- 15 jacks if the latter are correspondingly weakened, whereby the pawls themselves also require to be made considerably weaker, and thus possess a reduced power of resistance to withstand the attack of the cams.
- 20 It has also been proposed to mount the needles on special jacks forming the needle passage, and to move the heels of the needles into engagement with the cams by lifting these jacks. This method of mounting the needles, however, does not permit of a proper positive guiding thereof in the needle passage.
- 25 It is the object of the invention to overcome the disadvantages referred to, and this is accomplished by lifting and lowering the operating jacks, for the purpose of moving into or out of engagement with the cams, parallel to the walls of the passage by means of auxiliary jacks, which are capable of longitudinal sliding movement, and on which at the same time the operating jacks are caused to slide, whereby the latter remain in continuous engagement with the needle heels.
- 30 This arrangement possesses the advantage that the needles always remain positively coupled with the operating jacks, whilst the latter may be constructed in the same thickness as the needles and the auxiliary jacks,
- 35 so that even in the case of extremely fine

divisioning of the needle bed the operating jacks may be passed securely between the high sections of the needle passages and co-operate with the cams in exact fashion. Since furthermore the operating and auxiliary jacks may be of the same thickness as the needles, the production of all parts is extremely simple.

55 The invention will now be described more fully with reference to the accompanying drawing, which illustrates the invention in two possible forms of embodiment.

60 Fig. 1 is a cross-section through a needle bed of the knitting machine with lowered operating jack for the needle.

65 Fig. 2 is a similar view to Fig. 1 with the jack in elevated position.

70 Fig. 3 shows a modified form of the jack arrangement with the jack lowered, and

75 Fig. 4 a similar view to Fig. 3 with the jack raised.

In the bed 1 the needles 3 are guided in passages 2, and are secured in the known manner by a bar 4. The needles possess at the rear end the upwardly bent hooks 5, which are capable of being engaged by the operating jacks through the medium of the slot 7. The operating jacks 6 possess at the rear end a foot 8, which is capable of co-operating with the cam 9. The jack 6 is prevented from being lifted from the needle bed by means of two bars 10 and 11. The bar 10 at the same time also acts as stop for the longitudinal movement of the jack 6 in the one direction, and co-operates with a projection 12 on the said jack.

80 The operating jack 6 rests on a manually shiftable auxiliary jack 13, which may be moved backwards and forwards by means of a projection 14, and is prevented from being lifted from the needle bed 1 by a bar 15. This bar 15 acts simultaneously to limit the longitudinal movement of the auxiliary jack 13. This strikes in the advanced position with the projection 14 against the rear side of the bar 15, whilst for the purpose of limiting the movement in the opposite direction there is provided on the auxiliary jack 13 a projection 16, which is capable of mov-

ing against the bar 15 from the opposite side.

The operating jack 6 possesses two downwardly directed projections 17 and 18, which are furnished towards the needle side with two sloped portions 19 and 20. These projections engage in exactly corresponding recesses 21 and 22 in the auxiliary jack 13, which recesses also possess two sloped portions 23 and 24 corresponding with the parts 19 and 20. If the auxiliary jack 13 is withdrawn into the position according to Fig. 2, the portions 19 and 20 slide against 23 and 24, and the jack 6 is lifted up to the bars 10 and 11. Upon additional withdrawal of the auxiliary jack 13 the abutments 17 and 18 slide against the projections 25 and 26 on the auxiliary jack 13, which projections now act as bearing surfaces for the jack 6. The heel 8 of the jack 6 is now situated within reach of the cam 9.

Upon the advance movement of the jack 6 by the cam 9 the same slides on the projections 25 and 26 and is situated in the operative position to move the needles 3 as required.

If the jack 6 is to be lowered to such extent that its projection 8 no longer projects beyond the needle bed, and is accordingly situated out of reach of the cam 9, the auxiliary jack 13 is advanced up to the extent of the bar. The projections 17 and 18 then again coincide with the recesses 21 and 22, so that the jack 6 is lowered against the auxiliary jack 13.

In order, should the jack 6 become wedged, to ensure that the same is properly lowered, this jack is furnished at the front end with a sloped projection 27, and at the rear end with an inclined portion 28. Against these two portions 27 and 28 there move the sloped portions 29 and 30 on the auxiliary jack 13, so that these portions, in the extreme position, positively withdraw the jack 6 to such extent as to ensure that the same is moved out of reach of the cam 9.

For the purpose of also guiding the auxiliary jack 13 at the front, the projection 26 may possess a slot 31, which is engaged by a guide member 32.

According to Figs. 3 and 4, the operating jack 6a is only about half the length of that in Figs. 1 and 2. The same possesses merely one projection 17a having an inclined portion 19a. In this case the jack 6a slides only with the one projection 17a on the projection 25a of the auxiliary jack 13a, and may, therefore, readily tend to tip. To avoid this the front end of the jack 6a is furnished at the bottom with an abutment 33, by means of which the same, upon the advance movement by the cam, is

able to slide along the bottom of the passage 2a. Upon the lowering action the abutment moves into a recess 34 in the bed.

This recess 34 passes through the bed 1, and is conducted with its front end to such extent below the needles 3 that should a needle happen to break, which usually takes place at the bend of the hook 5, the broken part 5 is able to fall downwards out of the bed.

In the above the jacks according to Figs. 1 and 3 have been represented as being employed each for a particular machine, that is to say—either 6 or 6a. It is possible, however, to employ both types in the one machine disposed alternately to each other. In this case the machine requires to be furnished with two cam systems 9.

Instead of lifting the operating jacks by withdrawing the auxiliary jacks, it is also possible to adopt the reverse method, i. e., to lift the operating jacks by advancing the auxiliary jacks.

To prevent an unintended advance on the part of the auxiliary jacks, braking springs may be provided in the needle bed in the known manner, which springs hold the auxiliary jacks in their extreme positions.

When using two cam systems the needles may be of the same length; merely the length of the operating jacks varies accordingly.

It will be understood that no limitation is made to the specific forms of embodiment illustrated in the drawing, which have been quoted merely by way of example, and that various modifications are quite possible within the meaning of the above description and the annexed claims without departing from the spirit of the invention.

What I claim as new and desire to secure by Letters Patent is:

1. In a needle operating mechanism for straight bar knitting machines, operating jacks for moving the needles, cams for moving the said operating jacks, and longitudinally shiftable auxiliary jacks on which the said operating jacks are caused to slide, the said operating jacks being lifted and lowered by the said auxiliary jacks parallel to the walls of the needle passage and remaining in continuous engagement with the heels of the needles.

2. In a needle operating mechanism for straight bar knitting machines, operating jacks for moving the needles, cams for moving the said operating jacks, longitudinally shiftable auxiliary jacks on which the said operating jacks are caused to slide, projections on the said auxiliary jacks, and projections having sloped portions on the said operating jacks adapted to co-operate with the said projections on the auxiliary jacks.

3. In a needle operating mechanism for straight bar knitting machines, operating

jacks for moving the needles, cams for moving the said operating jacks, longitudinally shiftable auxiliary jacks on which the said operating jacks are caused to slide, and projections on the said auxiliary jacks co-operating with recesses having sloped guide portions in the said operating jacks.

4. In a needle operating mechanism for straight bar knitting machines, operating jacks for moving the needles, cams for moving the said operating jacks, longitudinally shiftable auxiliary jacks on which the said operating jacks are caused to slide, and abutments on the said operating jacks engaging in recesses in the needle bed.

5. In a needle operating mechanism for straight bar knitting machines, operating jacks for moving the needles, cams for moving the said operating jacks, longitudinally shiftable auxiliary jacks on which the said operating jacks are caused to slide, and passages in the needle bed for removal of the broken needles, abutments on the said operating jacks engaging with the openings of the said passages when the said operating jacks are in their lowered position.

6. In a needle operating mechanism for straight bar knitting machines, operating jacks for moving the needles, cams for moving the said operating jacks, longitudinally shiftable auxiliary jacks on which the said operating jacks are caused to slide, projections having sloped guide portions on the said operating jacks adapted to engage with correspondingly shaped recesses having sloped guide portions in the said auxiliary jacks, and abutments on the said operating jacks engaging in recesses in the needle bed.

40 In testimony whereof I affix my signature.

CARL BAUMGÄRTEL.
